UNITED STATES PATENT OFFICE.

HENRY F. STARRETT, OF CHICAGO, ILLINOIS.

KNIFE-SWITCH.

Specification of Letters Patent.

Patented May 30, 1916.

1,185,141.

Application filed May 13, 1912. Serial No. 696,925.

To all whom it may concern:

Be it known that I, HENRY F. STARRETT, a citizen of the United States, residing at Chicago, in the county of Cook and State of Illinois, have invented new and useful Improvements in Knife-Switches, of which the following is a full, clear, concise, and exact description, reference being had to the accompanying drawing, forming a part 10 of this specification.

My invention relates to improvements in knife switches, and particularly to knife switches adapted for use in connection with panel boards.

It has for one of its objects to provide a knife switch which may be removably mounted on the front of the panel board and in which the securing means may be readily accessible from the front of the 20 switch.

My invention is particularly designed for use in connection with the panel board base member shown and described in an application for U. S. Letters Patent filed by me

25 June 13, 1911, Serial No. 632,883.

For the purpose of disclosing my invention I have illustrated one embodiment thereof in the accompanying drawings, in which—

30 Figure 1 is a side elevation, partly in section, of a knife switch embodying my invention; Fig. 2 is a front elevation of the switch; Fig. 3 is a detail section taken on the line 3—3 of Fig. 1; Fig. 4 is a plan view 35 of a blank from which the clips are adapted to be formed; Fig. 5 is a perspective view of one of the bracket clips; and Fig. 6 is a perspective view of one of the anchor studs of the panel board base member.

40 The switch illustrated in the accompanying drawings is shown mounted upon a panel board having the characteristics as disclosed in the above-mentioned application. I have not illustrated in detail this

45 panel board, as the same forms no part of the present invention, but have shown sufficient of the panel board to illustrate the manner of mounting the switch. This panel board base member comprises an insulating 50 base 1 which may be of slate or other usual material, and on the back of the panel board are mounted the bus bars (not shown) and connector bars 2. These bus bars and connector bars form the distributing conductors 55 mounted on the rear of the base and are permanently secured in position by means of

anchor studs. Each anchor stud is provided with a flat head 4 adapted to engage the front face of the base and has its stem 5 arranged to extend through an opening in the 60 base and through one of the connector bars or bus bars, as the case may be. The ends of the stem are swaged over, as at 6, and covered by solder to make a firm electrical and mechanical contact with the distributing conductor. In the front face of the anchor stud 65 a screw-threaded socket is provided for receiving the screw by means of which the clips of the switch are secured in position.

The knife switch comprises a pair of 70 bracket clips 7, a pair of contact clips 8 and a pair of knife blades 9. Each blade is pivotally mounted between the arms of the bracket clips and the front ends of the blades are connected together by a suitable insulating handle 10 in which the front ends are adapted to be embedded. The bracket clips and contact clips are of the same general construction, being changed merely in slight details to adapt them to their different functions. Each clip comprises a base 11 having a longitudinal extension 12 in which is formed the opening 13 to permit the securing screw 14 to pass therethrough and engage in the screw-threaded socket in the anchor stud and a pair of spring arms or fingers 15 integrally formed with and bent upwardly from the base 11. These arms are sprung toward each other at their upper ends to closely engage the knife blades and 90 are provided with longitudinally extending bracing webs 16 which connect them with the extension 12 of the base. The arms of the bracket clips are provided with openings 17 through which extend the rivets 18 upon 95 which are pivoted the rear ends of the knife blades 9, a spring washer 19 being interposed between one of the heads of the rivets and one of the arms of the bracket clips to assist in making a close electrical contact 100 between the arms and the knife blade.

The base of the clip has a pair of downwardly extending projections 20, preferably formed by punching up the metal, which projections are arranged to engage in a 105 transverse slot 21 formed in the head of the anchor stud to prevent the clips from turning on the stud.

The contact clips, as before stated, are of the same construction as the bracket clips, 110 with the exception that they are not provided with the opening to receive the pivot

rivet and are provided with stop lugs 21, preferably formed by striking up the metal at the proper point, which limit the downward movement of the knife blades. The 5 tops of the arms are also flared outwardly to assist in guiding the knife blades between the arms.

In forming the clips I preferably form the same from a blank, such as is shown in 10 Fig. 4. This blank, as illustrated, is formed from a thin strip of material having at its central portion a rearward extension 22. Before the blank is bent, the opening for receiving the securing screw is formed there- 15 in, the lugs 20 are struck up therein, and if the blank is to form a bracket clip the openings for the pivot rivet 18 are formed, and if the blank is for a contact clip the lugs 21 are struck up. The blank is then bent up 20 along lines extending inside the outer ends of the projection 22, so that when the arms are turned up that portion of the lug 22 turned up therewith forms the webs 16.

By the provision of the offset base or longitudinal extension of the base, I am enabled 25 to so locate the opening through which the securing screw passes that access may be readily obtained thereto from the front by a screw driver, so that the securing screw may 30 be fastened in position from the front of the clip. In ordinary practice it is impossible to secure the clip of a knife blade switch in position due to the fact that the spring arms 35 are so close together that a screw driver could not be inserted between them, but by my arrangement, while I have not sacrificed anything in strength, I have provided a means whereby access may be had to the securing screw from the front. Furthermore,

by the provision of the bracing webs 16 any 40 danger of side strain breaking the longitudinal extension of the base is prevented, and these bracing webs additionally strengthen the spring arms and give them an additional clamping action. 45

While I have shown and described one form of switch in which my invention is embodied, it will be understood that various changes may be made in the switch shown and that the invention may be embodied in 50 other forms of knife switches without departing from the spirit of my invention as set forth in the appended claim.

Having thus described my invention, what I claim as new and desire to secure by Letters Patent, is:—

The combination with an insulating base, of an anchor stud extending therethrough and permanently fastened thereon having a screw-threaded recess in the front face thereof and a transversely extending slot across the front face thereof, a knife switch clip secured to said stud and comprising a bottom having an extension in which the holding screw opening is formed, downwardly extending aligned projections on either side of said opening engaging in the slot with their anchor stud to prevent the clip from turning when secured to said stud, and integral upwardly extending spaced apart spring 70 arms on said bottom.

In witness whereof, I have hereunto subscribed my name in the presence of two witnesses.

HENRY F. STARRETT.
